GAME OR TOY

Filed Nov. 27, 1929

UNITED STATES PATENT OFFICE

GEORGE H. JOHNS, OF NEW HAVEN, CONNECTICUT, ASSIGNOR OF ONE-HALF TO STEVE MUSTAKOS, OF NEW HAVEN, CONNECTICUT

GAME OR TOY

Application filed November 27, 1929. Serial No. 410,125.

This invention relates to games or toys, and more particularly to a game in which an object or projectile is thrown into the air by a device operated by means of a spring or some other source of power, the object or projectile being designed to fall upon a distant spot. Preferably, I propose that the target or surface upon which the object is intended to fall shall be kept in motion and it shall be the object of the player to release the projectile at the proper time so that it will fall upon the proper section of the target.

In the form of my device illustrated, the projectile is in the form of a figure or doll and is mounted upon a base provided with a spike or point, whereby the point will pierce the target and the figure will remain in upright position thereon.

Also in the form of my device illustrated I provide projecting means in the form of a shaft mounted to rock and so arranged that when the figure or projectile is placed in position to be released, a spring or other tension means secured to the shaft will be placed under tension to provide the power necessary to propel the object.

One object of my invention is to provide a game or toy which will be entertaining and attractive.

Another object of my invention is to provide a game which will require a degree of skill in its operation and which will be entertaining and attractive.

A still further object of the invention is the provision of a game or toy of the character described which may be economically made, which will be comprised of comparatively few parts and which will be simple in operation.

A still further object of this invention is the provision of an entertaining and attractive game device which will consist of relatively few moving parts which are unlikely to get out of order, and which will be relatively cheap to manufacture.

To these and other ends, the invention consists in the novel features and combinations of parts to be hereinafter described and claimed.

In the accompanying drawings:

Fig. 1 is a perspective view of a toy or game device embodying my invention;

Fig. 2 is a sectional view on line 2—2 of Fig. 1;

Fig. 3 is a sectional view on line 3—3 of Fig. 2;

Fig. 4 is a somewhat diagrammatic view showing the path of the projectile, and

Fig. 5 is an enlarged fragmentary sectional view similar to Fig. 3, but showing the parts in another position.

To illustrate a preferred embodiment of my invention I have shown a frame comprising a horizontal portion 10 and a vertical portion 11, within which the parts of the device are mounted. The vertical portion 11 may comprise a pair of side members 12 and 13 in which is rotatably mounted a shaft 14. A pair of sheaves or pulleys 15 and 16 are non-rotatably secured to this shaft by means of the set screws 17.

Springs 18 and 19 are provided, each of these springs having one end connected to one of the pulleys, as at 20, and the other end connected to a block 21 by means of screw eyes 22. The block 21 may be secured between the upright frame members 12 and 13 in any desired manner. It will be obvious that this block will be placed in position to properly tension the springs 18 and 19, and if a finer adjustment of the spring tension is desired this may be obtained by means of the screw eyes 22, which may be screwed in or backed out of the block 21.

It will be obvious that the sheaves or pulleys 15 and 16 act as crank arms to tension the springs 18 and 19 when the shaft 14 is turned from the position shown in Fig. 5 to that shown in Fig. 3. While some other form of crank arm might be provided, it will be found that the sheave or pulley is quite advantageous in that the spring is always maintained at a distance from the shaft equal to the radius of the pulley so that when the projectile is released, as will be later explained, the shaft quickly gathers momentum.

Also mounted upon the shaft 14 and preferably adjacent the center thereof is a member 23 non-rotatably secured to the shaft by means of the set screw 24. The end of this

member opposite the set screw is provided with a bore or recess 25, adapted to receive a pin 26 secured upon one end of the projectile. This pin fits relatively freely into the bore 25 so that at the proper time the projectile will be thrown from the apparatus.

The projectile as shown, comprises a doll or figure 27, the pin 26 being mounted upon the head thereof and the figure being shown 10 as standing upon a base 28 to which it is secured, the base being provided with a spike or sharp point 29. The base 28 will preferably be relatively heavy whereby the figure when projected from the apparatus will always fall 15 upon the point 29.

Within the portion 10 of the frame is a horizontally arranged support 30 upon which are mounted a pair of U-shaped members 31 and 32, having their free ends upstanding 20 from the support 30. A lever 33 is pivoted between its ends to the free ends of the U-shaped member 32, and the heavier end thereof of preferably being directed toward the member 31. Similarly, a lever 34 is pivoted to the 25 U-shaped member 31, the heavier end of this lever, however, being directed toward the member 32 and lying below the heavier end of the lever 33. Above the lighter end of the lever 34 is a push-pin 35, by which this lever 30 may be manually operated. It will be apparent that when the levers 33 and 34 are arranged as described, they will tend by gravity to return to and remain in the position shown in full lines in Fig. 3, with the rear end of the lever 34 elevated and the front end of the lever 33 elevated. The reason for this 35 will presently appear.

Above the shaft 14 is provided a stop member 36 designed to be engaged by the member 23 when the latter is in the position shown 40 in Fig. 5. This stop member may preferably be made of rubber or some sound deadening and shock absorbing material, and may be secured to the upper frame member 37.

45 A target 38 is mounted in front of the frame portion 11, the target preferably being rotatably mounted on a suitable support such as 39, and may be rotated by means of the belt 40, driven from any suitable source of power. 50 This target will preferably be divided into sections or sectors 41, each of which may bear a number or be distinctively colored so that the points to which the player is entitled will be determined by the sector upon which the figure or projectile alights.

The operation of my device is as follows. Assuming the parts of the apparatus are in the position shown in Fig. 5, the player places the stem 26 on the head of the figure or doll, 60 within the bore 25 of the member 23. The figure is then brought downwardly into the position shown in Fig. 3. During this movement, the forward end of the lever 33 will be depressed by the point 29, but as soon as this 65 point passes the end of the lever the latter will

automatically move upwardly into the position shown in full lines in Fig. 3, and secure the figure in place. During this time, the lever 34 has remained stationary in the position shown in full lines in Fig. 3.

70 It will be apparent that as the member 23 is moved from the position shown in Fig. 5, to that shown in Fig. 3, the shaft 14 will be rotated or rocked through a partial revolution and the springs 18 and 19 will be placed 75 under tension. The device is now set for operation, the lever 33 acting as the trigger which will release the projectile which, in this instance, is the doll. The player watches the target 38, which is rotating at a relatively slow speed and at the instant which is thought to be proper to cause the projectile to strike the highest numbered sector of the target, presses the push-pin 35. This moves the levers 33 and 34 into the dotted line position shown in Fig. 3 and releases the pin 29 from the end of the lever 33.

80 The springs 18 and 19 rotate the shaft 14 pulling the member 23, carrying the projectile 27 against the stop 36. When the member 23 strikes this stop the stem 26 is dislodged from the bore 25 and the inertia of the projectile causes it to continue its motion over a path shown approximately in dotted lines in Fig. 4, causing the figure to make 85 a complete rotation in the air and to alight upon the point 29 upon the target.

90 While I have shown and described a preferred embodiment of my invention, it is to be understood that it is not to be limited to all of the details shown but is capable of modification and variation within the spirit of the invention and the scope of the appended claims.

95 What I claim is:

100 1. In a game or toy, a projecting device, a projectile attached thereto, actuating means for said projecting device, and a trigger device engaging said projectile to hold said actuating means under tension.

105 2. In a game or toy, a projecting device, a projectile attached thereto, actuating means for said projecting device, and a trigger device engaging said projectile to hold said actuating means under tension, and means 110 to release the trigger device to permit the actuating means to propel the projectile.

115 3. In a game or toy, a projecting device and tension operated actuating means therefor, a trigger device and a projectile engaged with said projecting device and with said trigger device to hold said actuating means under tension.

120 4. In a game or toy, a projecting device and tension operated actuating means therefor, a trigger device, a projectile engaged at one end with said projecting device and at the other end with said trigger device to hold said actuating means under tension.

125 5. A game or toy comprising a projecting 130

device, spring means to operate said device, a trigger device, a projectile having projections at opposite ends thereof, one of which is engaged with said projecting device and the other engaged with said trigger device to hold the spring under tension, and means for releasing the projectile from said trigger.

6. A game or toy comprising a projecting device, spring means to operate said device, a trigger device, a projectile having projections at opposite ends thereof one of which is engaged with said projecting device and the other engaged with said trigger device to hold the spring under tension, means for releasing the projectile from said trigger, and means for abruptly checking the movement of said projecting device.

7. In a game or toy, a rock shaft, spring means to actuate said shaft, a member secured upon said shaft provided with attaching means for a projectile, a projectile arranged with complementary attaching means, trigger means to hold said shaft in position to place the spring means under tension, and means to release said trigger means.

8. In a game or toy, a rock shaft, spring means to actuate said shaft, a member secured upon said shaft provided with attaching means for a projectile, a projectile arranged with complementary attaching means, trigger means to hold said shaft in position to place the spring means under tension, means to release said trigger means, and means to effect the detaching of the projectile at a predetermined time in the movement of said rock shaft.

9. In a game or toy, a frame, a rock shaft mounted upon said frame, spring means to actuate said shaft, a member secured to said shaft and having an opening therein, a projectile having a projecting member designed to enter said opening, trigger means engaging said projectile when the latter is in position to hold said spring under tension, and means to release said trigger means.

10. In a game or toy, a frame, a rock shaft mounted upon said frame, spring means to actuate said shaft, a member secured to said shaft and having an opening therein, a projectile having a projecting member designed to enter said opening, a movable member designed to engage said projectile to hold the spring under tension, and manually operable means to release the projectile from said member.

11. In a game or toy, a frame, a rock shaft mounted upon said frame, spring means to actuate said shaft, a member secured to said shaft and having an opening therein, a projectile having a projecting member designed to enter said opening, a movable member designed to engage said projectile to hold the spring under tension, manually operable means to release the projectile from said member, said movable means comprising a

lever pivoted between its ends and having one end engaged with said projectile.

12. In a game or toy, a frame, a rock shaft mounted upon said frame, spring means to actuate said shaft, a member secured to said shaft and having an opening therein, a projectile having a projecting member designed to enter said opening, a movable member designed to engage said projectile to hold the spring under tension, manually operable means to release the projectile from said member, said movable means comprising a lever pivoted between its ends and having one end engaged with said projectile, and said manually operable means comprising a second lever engaged with the first-named lever and being accessible for manual operation.

13. In a game or toy, a moving target, a frame, a rock shaft mounted in the frame, and spring means to actuate said shaft, a member secured to said shaft and having an opening therein, a projectile having a stem at one end adapted to be received in said opening to detachably connect the projectile with the shaft, said projectile having a spike at the other end thereof, a trigger device engaging said spike when said projectile is engaged with said member and in position to hold the spring under tension, means for releasing the trigger device from said spike, and means for checking the rotation of said shaft at a predetermined time to cause the projectile to be propelled by said device and the projectile spike to strike said target.

14. In a game or toy, a moving target, a frame, a rock shaft mounted in the frame and spring means to actuate said shaft, a member secured to said shaft and having an opening therein, a projectile having a stem at one end adapted to be received in said opening to detachably connect the projectile with the shaft, said projectile having a spike at the other end thereof, a trigger device engaging said spike when said projectile is engaged with said member and in position to hold the spring under tension, comprising a lever engaged with said spike, a second lever engaged with the first lever, and manually operable means to actuate the second lever to cause movement of said first lever to release said spike and effect the propulsion of said projectile by said spring means.

In witness whereof, I have hereunto set my hand this 26th day of November, 1929.

GEORGE H. JOHNS.
